UNITED STATES PATENT OFFICE.

HARRISON D. BOYER, OF PHILADELPHIA, PENNSYLVANIA.

DESIGN FOR A SEAT-BODY FOR CHILDREN'S VEHICLES.

58,065.

Specification for Design.

Patented June 7, 1921.

Application filed November 6, 1920. Serial No. 422,404. Term of patent 14 years.

To all whom it may concern:

Be it known that I, HARRISON D. BOYER, a citizen of the United States, residing at Philadelphia, in the county of Philadelphia and State of Pennsylvania, have invented a new, original, and ornamental Design for a Seat-Body for Children's Vehicles, of which the following is a specification, reference being had to the accompanying drawing, forming a part thereof.

Figure 1, is a plan view of the seat-body

for children's vehicles, showing my new design; and

Fig. 2, is an edge view thereof.

I claim:

The ornamental design for seat-body for children's vehicles, as shown.

HARRISON D. BOYER.
